UTILITY TRAY

Jacob Gaines Heim, Alhambra, Calif., assignor
of one-half to The Calpat Corporation, Los
Angeles, Calif., a corporation of California

Application January 23, 1950; Serial No. 140,056

2 Claims. (Cl. 45—28)

1

This invention relates to improvements in trays, and more particularly to a tray adapted to be mounted upon the wall of a receptacle or upon the dividing wall between two receptacles.

It is customary, at the present time, to equip kitchens with double sinks which consist of two juxtaposed basins divided from each other by a common dividing or partition wall. The opposite ends of such double sinks usually terminate adjacent tiled or linoleum covered working surfaces but, when operations are being carried on in the two basins, it is frequently necessary to support a vessel being cleansed or food being washed upon the dividing partition between the two basins. Since the top of the dividing wall or partition is not sufficiently wide to provide a suitable working surface, recourse is frequently had to the adjacent tile or linoleum covered working surfaces.

In addition, it is not desirable to perform certain operations, such as the scouring of pans or the cleaning of fish and poultry on the working surfaces adjacent the opposite ends of the sink and such operations are usually conducted in the bottom of the basin with consequent strain upon the back of the individual doing the scouring or the cleansing and with generally unsatisfactory results.

It is, therefore, a primary object of my invention to provide a utility tray adapted to be mounted upon the dividing wall between adjacent basins of a double sink which supplies an auxiliary working surface upon which articles being cleansed or prepared may be supported. Although I show and describe the utility tray of my invention as mounted upon the dividing wall between two basins of a double sink, it is obvious that the utility tray may be mounted upon the peripheral wall of a tub or similar vessel, if so desired.

When dishes are being washed in adjacent basins of the double sink and are transferred from the washing basin to the rinsing basin, it occasionally happens that the dish or other utensil being transferred is struck against the dividing wall between the basins and thus broken.

It is an additional object of my invention to provide a utility tray adapted to be mounted upon the dividing wall between the two basins of a double sink which is formed of a resilient material such as rubber and which is adapted to serve as a guard to prevent the breakage of dishes upon the dividing wall as they are transferred from one basin of the sink to the other.

A further object of my invention is the pro-

2

vision in a utility tray of the aforementioned type of one or more receptacles adapted to receive bars of soap or containers for scouring powder and detergents to permit ready access to the same by the user thereof.

Another object of my invention is the provision of a utility tray of the aforementioned type which consists of a working surface which rests upon the top of the dividing wall between the two basins of the double sink and which includes oppositely disposed legs adapted to engage the opposite sides of the dividing wall to maintain the working surface in position upon the top of the dividing wall.

15. A further object of my invention is the provision of a utility tray of the aforementioned type in which the legs thereof are formed integrally with the working surface and are sufficiently resilient to permit the opposite sides of 20 the dividing wall between the two basins of the double sink to be engaged thereby.

Another object of my invention is the provision of a utility tray of the aforementioned type in which the legs thereof are provided with 25 securing means adapted to materially augment the engagement of said legs with the opposite sides of the dividing wall between the two basins of the double sink.

Other objects and advantages of my invention 30 will be apparent from the following specification and the accompanying drawing, which is for the purpose of illustration only, and in which:

Fig. 1 is a perspective view showing a utility tray constructed in accordance with my invention and mounted upon the dividing wall between the two basins of a double sink;

Fig. 2 is a vertical, sectional view taken on the broken line 2—2 of Fig. 1;

Fig. 3 is a perspective view showing another 40 embodiment of my invention;

Fig. 4 is a vertical sectional view taken on the broken line 4—4 of Fig. 3;

Fig. 5 is a fragmentary, side elevational view of a modification of the utility tray of my invention;

Fig. 6 is a vertical, partly sectional view taken on the broken line 6—6 of Fig. 5;

Fig. 7 is a perspective view of another embodiment of my invention; and

50 Fig. 8 is a vertical, partly sectional view taken on the broken line 8—8 of Fig. 7.

Referring to the drawing and particularly to Fig. 1 thereof, I show a double sink 10 which includes juxtaposed basins 11 and 12 separated from each other by a common dividing wall 14;

3

the opposite sides 15 and 16, respectively, providing one wall of the basins 11 and 12. The opposite side walls 15 and 16 of the dividing wall 14 terminate in a top 17 upon which rests a utility tray 20 constructed in accordance with my invention.

The utility tray 20 provides a substantially rectangular working surface 21 having attached thereto or integrally formed therewith oppositely disposed, downwardly extending legs 23 and 24. The under side 28 of the working surface 21 is so formed that its configuration is substantially identical with the configuration of the top 17 of the dividing wall 14 so that the utility tray rests snugly upon said top. The surface 21 of the utility tray 20 is provided with a plurality of corrugations 27 to prevent the inadvertent dislodgement of objects disposed upon said working surface.

In order that the utility tray 20 may serve the additional function of acting as a guard to prevent the breakage of dishes or other utensils when accidentally struck against the dividing wall 14, I prefer to manufacture the tray of rubber or similar resilient material. When the tray is formed of rubber, the legs 23 and 24 are molded integrally therewith and possess sufficient inherent resilience to cause them to intimately engage, respectively, the opposite sides 15 and 16 of the dividing wall 14. Formed integrally in the oppositely disposed legs 23 and 24 are securing means 29 constituted, in the present instance, by suction cups 30 which, when the outsides of the legs 23 and 24 are properly compressed, serve to materially augment the engagement of said legs with the side walls 15 and 16.

Shown in Figs. 3 and 4 of the drawing is an alternative embodiment of my invention in the description of which identical reference numerals will be utilized to describe those portions of the utility tray which are identical with those of the previously discussed embodiment.

The utility tray 32 of the alternative embodiment of my invention provides a working surface 21 which has integrally formed therewith or attached thereto depending legs 23 and 24. The intermediate portion of the working surface 21 is provided with a plurality of transverse corrugations 34 and formed in opposite ends of said surface adjacent the intermediate corrugated portion thereof are receptacles 35 and 36. The receptacles 35 and 36 are designed to receive bars of soap and containers for scouring powder or detergent to be utilized in the cleaning of utensils in the double sink 10. Communicating with the interior of the receptacle 35 is a drainage opening or channel 38 which is adapted to permit excess moisture to be drained from said receptacle.

To materially increase the width afforded by the working surface 21 of the utility tray 32, I provide an auxiliary working surface constituted by an elongated plank or board 40 having formed in the under side thereof a longitudinal groove or channel 41 which is adapted to receive the working surface 21 of the utility tray 32 to permit the board 40 to be securely mounted thereupon.

Shown in Figs. 5 and 6 of the drawing are structural modifications adapted to be incorporated in the alternative embodiments of the utility tray. A plurality of diagonal channels 42 is formed in the leg 23 of the utility tray 45 and disposed between adjacent channels 42 is a supporting means 43 constituted by a plurality of brackets 44 formed integrally with said leg 23. As best seen in Fig. 6 of the drawing, the brackets

4

44 are adapted to support a cake 46 of soap or similar cleanser.

Formed integrally with the opposite side of the utility tray 45 is a bar 47 which is suitably reinforced by reinforcing means 48 and which is adapted to support a dishcloth or other cleaning implement. The lower portion of the reinforcing means 48 extends downwardly into the leg 24 of the utility tray 45 and constitutes, since the reinforcing means 48 is formed of spring wire stock, a securing means 49 which is adapted to cause the inward movement of the leg 24 to materially augment the engagement of said leg with the side 16 of the dividing wall 14 between the basins 11 and 12 of the double sink 10. Although only one securing means 49 is shown, it is obvious that additional securing means may be molded integrally in the oppositely disposed leg 23.

Another embodiment of my invention is shown in Figs. 7 and 8 of the drawing and consists in a utility tray 51 which provides a substantially cup-shaped working surface 52 which has attached to the under side thereof or formed integrally therewith legs 53 and 54. The cup-shaped working surface 52 may be used as a receptacle for garbage scraped from plates about to be washed and may also be used as a depository for unwanted portions of vegetables and other produce cleaned in the sink 10. Provided at the base of the cup-shaped working surface 52 is a plurality of drainage openings 56 which are adapted to permit the drainage of liquids contained in the discarded material into the basins 11 and 12. When a sufficient amount of discarded material has collected in the cup-shaped portion 52 of the utility tray 51, it may be removed from its position on the dividing wall 14 to permit the materials contained therein to be placed in a proper receptacle.

I thus provide by my invention a utility tray which offers an auxiliary working surface to permit the cleaning of utensils, food products and other devices and materials thereupon. In addition, the utility tray when formed of a suitable resilient material, serves as a guard to prevent the breakage of utensils upon the dividing wall upon which it is mounted. By another embodiment of my utility tray I also provide an auxiliary working surface which is adapted to receive discarded materials and to act as a temporary receptacle therefor while permitting the drainage of fluids from the materials as they remain in the receptacle.

Although I have shown and described preferred embodiments of my invention for the purpose of illustrating the construction and mode of utilization of my invention, it is obvious that changes, alterations and modifications may be made in the details of construction and I, therefore, do not desire to be limited to such specific details but prefer, rather, to be afforded the full scope of the claims.

I claim as my invention:

1. A sink guard mountable on the transverse wall between the basins of a two-basin sink including a working surface, said working surface being of elongated rectangular configuration and having formed integrally therewith a pair of resilient legs which depend therebelow and have root portions whose transverse dimensions are substantially twice the dimensions of their extreme lowermost ends, the vertical lengths of said legs being substantially greater than the transverse dimension of said working surface and the inner sides of said legs engaging the entire under-

lying surfaces of the opposite sides of said wall, at least one of said legs being provided with an auxiliary spring member embedded therein, said spring member extending upwardly into the underside of said working surface and projecting laterally therefrom to define a hanger for dishcloths or similar articles, and at least one of said legs being provided with a laterally extending seat to constitute an auxiliary receptacle thereupon.

2. In a sink guard construction, the combination of: a sink having a continuous peripheral wall and a transverse wall extending between oppositely disposed portions of said peripheral wall to define a pair of basins on opposite sides of said transverse wall; and a sink guard mounted on said transverse wall between said basins, said sink guard including a working surface of elongated, rectangular configuration having a pair of resilient legs integrally formed therewith and depending therebelow, the root portions of said legs having transverse dimensions substantially twice the dimensions of their extreme lowermost ends and the vertical lengths of said legs being sub-

stantially greater than the transverse dimension of said working surface to permit said legs to terminate closely adjacent the bottom of said transverse wall, while the inner sides of said legs engage the entire underlying surfaces of the opposite sides of said wall, at least one of said legs being provided with an auxiliary spring member embedded therein, said spring member extending upwardly into the underside of said working surface and projecting laterally therefrom to define a hanger for dishcloths or similar articles, and at least one of said legs being provided with a laterally extending seat to constitute an auxiliary receptacle thereupon.
